(57) **CLAIM**

The ornamental design for a fence post support system, as shown and described.

DESCRIPTION

FIG. 1 is a front, first side, and top perspective view of a fence post support system;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof; and,

FIG. 8 is a front, first side, and top perspective view thereof, with a fence post coupled to an interior portion of the fence post support system.

The broken line portions of the figure drawings are included to show unclaimed subject matter only for the purpose of illustrating environment and forms no part of the claimed design.
